UNITED STATES PATENT OFFICE

1,974,582

BRAKE

Humphrey F. Parker, South Bend, Ind., assignor
to Bendix Brake Company, South Bend, Ind., a
corporation of Illinois

Application May 17, 1930, Serial No. 453,386

5 Claims. (Cl. 188—78)

This invention relates to brakes and more particularly to internal expanding brakes.

It is well established that if two flat surfaces are brought in contact with each other, the friction between them is the product of the pressure forcing them together and the co-efficient of the friction of the surface. In a brake shoe, the frictional force is dependent not only upon these factors, but also upon the angle of approach which differs at different points of the shoe surface.

It is the aim of the present invention to provide a structure wherein the pressure is applied to the brake shoe in such a manner that it will more perfectly conform to a rotatable drum.

15 A major object of the invention is to provide means for applying the frictional members so that they will perfectly conform to the drum.

Another object of the invention is to provide means for applying the frictional members at 20 points removed from the respective ends of the frictional members.

25 Yet a further object of the invention is to provide a suitable structure for applying the frictional members, so that they will perfectly conform and that the respective ends of the frictional members will perform as efficiently as other portions of the frictional members.

A feature of the invention is to provide a friction member with pivotal links arranged in 30 spaced relation from the respective ends of the member, so that the member may be uniformly applied to a rotatable drum.

35 A further feature of the invention is to provide a brake which has the advantages of positive application of the frictional members, a brake which is highly efficient in operation and yet of marked simplicity as a whole in respect to each of its component parts, so that its manufacture may be economically facilitated both as regards to parts 40 and their assembly.

Other objects of the invention will appear from the following description taken in connection with the drawing, which forms a part of this specification, and in which:

45 Figure 1 is a side elevation of a brake illustrating the invention as applied.

Figure 2 is a sectional view substantially on line 2—2, Figure 1.

Figure 3 is a sectional view substantially on line 50 3—3, Figure 1.

Figure 4 is a modified form of the invention, and

Figure 5 is a sectional view substantially on line 55 5—5, Figure 4.

55 In the embodiment illustrated, there is pro-

vided a conventional rotatable drum 10 at the open side of which is a stationary support such as a backing plate 11. Positioned on the backing plate are anchors 12 and 13 and steady rests 14 and 15. Mounted for movement on the plate 60 is a primary shoe 16 and a secondary shoe 17. As shown, these shoes are interchangeable and each comprises a rim 18 to which is suitably secured a lining 19 adapted to engage the drum and a flange 20 cut away as at 21 and 22 to 65 lend flexibility to the shoes.

Although this particular type of shoe is described, it is to be understood that applicant in no way limits his invention to this precise form, as other forms of shoes may be used with equally 70 good effect, provided the rim is sufficiently flexible to conform to the radius of the drum.

The articulating ends of the shoes have a web portion 23 apertured to receive the respective steady rests 14 and 15 and these web portions are 75 connected by a suitable adjusting screw 24 of any preferred type.

Due to the cut away portions 21 and 22, there is formed in spaced relation to the other end of the primary and secondary shoes a web portion 80 25 to which is pivotally secured, as by a bolt 26, a link 27 apertured to receive the respective anchors 12 and 13 and having rounded shouldered portions 28 and 29. As shown, the links 27 are connected by a coil spring 30 and the primary 85 shoe is connected by a coil spring 31 to a fixed support 32. These springs serve to return the shoes to the off position.

Positioned between the shoulders 28 and 29 of the shoes is a cam 33 operable through a 90 shaft 34. The cam is provided with rotatable members 35 and 36 adaptable for engagement with the shoulders 27 and 28 upon the primary and secondary shoes.

In Figure 4, I have shown a modification 95 wherein the spring 30 is connected between shoes of a rigid type. In this embodiment of the invention the angle of approach is sufficiently removed from the toe of the shoe to cause the respective ends of the shoe to engage the drum with 100 substantially equal effect as other portions of the shoe.

Upon actuating the cam 33 to spread the shoes apart for engagement with the drum 10, the force of application of the shoes is at a point spaced 105 from the ends adjacent the anchors. Hence, a more uniform application of the frictional members to the drum may be attained.

Although this invention has been described in connection with certain specific embodiments, the 110

principles involved are susceptible of numerous other applications that will readily occur to persons skilled in the art. The invention is, therefore, to be limited only as indicated by the scope 5 of the appended claims.

Having thus described the various features of the invention, what I claim as new and desire to secure by Letters Patent is:

1. A brake comprising a rotatable drum, a fixed support associated therewith, shoes movably positioned on the support, a member adjustably connecting the articulating ends of the shoes, links pivoted on the shoes in spaced relation from the other ends of the shoes, anchors engaged by 10 the links, shoulders on the links, a cam positioned between the shoulders and a coil spring connected between the shoes.
2. A brake having a drum and friction means comprising two anchorages forming the ends of 20 said friction means, one effective when the drum is turning in one direction and the other effective when the drum is turning in the other direction, one of said anchorages being constructed and arranged to permit radial movement of the adjacent 25 portion of the friction means, and an applying lever having parts in disconnected thrust engagement with the ends of the friction means and operative to pry said ends apart to apply the brake.
3. A brake having a drum and friction means comprising two anchorages forming the ends of 30 said friction means, one effective when the drum is turning in one direction and the other effective

when the drum is turning in the other direction, both of said anchorages being constructed and arranged to permit radial movement of the adjacent portion of the friction means, and an applying lever having parts in disconnected thrust engagement with the ends of the friction means and operative to pry said ends apart to apply the brake.

4. A brake having a drum and friction means comprising two anchorages forming the ends of 85 said friction means, one effective when the drum is turning in one direction and the other effective when the drum is turning in the other direction, one of said anchorages comprising a pivoted link permitting the adjacent portion of the friction 90 means to shift radially, and a floating applying lever having thrust parts in direct disconnected thrust engagement with the ends of the friction means and operative to pry said ends apart to apply the brake.

5. A brake having a drum and friction means comprising two anchorages forming the ends of 95 said friction means, one effective when the drum is turning in one direction and the other effective when the drum is turning in the other direction, 100 said anchorages comprising pivoted links permitting the adjacent portions of the friction means to shift radially, and a floating applying lever having thrust parts in direct disconnected thrust engagement with the ends of the friction 105 means and operative to pry said ends apart to apply the brake.
